Primary Examiner — Kelley A Donnelly(74) *Attorney, Agent, or Firm* — Mark Murphey Henry(57) **CLAIM**

The ornamental design for a four receptacle serving tray with platform, as shown and described.

DESCRIPTION

Improved version of U.S. application Ser. Nos. 29/654,632 and 29/654,643 by the original inventor.

FIG. 1 is a perspective of the four receptacle tray with platform.

FIG. 2 is a right-side view of the four receptacle tray with platform.

FIG. 3 is a top view of the four receptacle tray with platform.

FIG. 4 is a front view of the four receptacle tray with platform.

FIG. 5 is a back view of the four receptacle tray with platform.

FIG. 6 is a top view of the four receptacle tray with platform; and,

FIG. 7 is a bottom view of the four receptacle tray with platform.

1 Claim, 4 Drawing Sheets(56)
